161,870

FISH LURE

Melkiah Edward Pope, Montrose, Calif.

Application August 27, 1949, Serial No. 4,733

Term of patent 14 years

(Cl. D31—4)

To all whom it may concern:

Be it known that I, Melkiah Edward Pope, a citizen of the United States, residing at Montrose, Los Angeles County, California, have invented a new, original, and ornamental Design for a Fish Lure, of which the following is a specification, reference being had to the accompanying drawing, forming a part hereof.

I claim:

The ornamental design for a fish lure, as shown.
MELKIAH EDWARD POPE.
